UNITED STATES PATENT OFFICE.

MORRIS F. SMITH, OF PHILADELPHIA, PENNSYLVANIA, ASSIGNOR OF ONE-HALF TO THE WILLIAM CRAMP & SONS SHIP AND ENGINE BUILDING COMPANY, OF PENNSYLVANIA.

ADJUSTING DEVICE FOR RIFLING GUNS OR CANNON.

SPECIFICATION forming part of Letters Patent No. 499,683, dated June 13, 1893.

Application filed June 30, 1892. Serial No. 438,494. (No model.)

To all whom it may concern:

Be it known that I, MORRIS F. SMITH, a citizen of the United States, residing in the city of Philadelphia, county of Philadelphia, and

5 State of Pennsylvania, have invented a new and Improved Device for Rifling Guns or Cannon, of which the following is a specification, reference being had to the accompanying drawings, and to the letters of reference
10 marked thereon.

The principal object of my invention is to provide rifling machines with an adjusting device of simple character, by means of which the gun may be accurately adjusted on its
15 axis to accommodate the rifling tool, or the tool adjusted on its axis as desired.

In the accompanying drawings:—Figure 1, is a plan view of a gun rifling machine having my invention applied thereto. Fig. 2, is
20 a side elevation of the same. Fig. 3, is an elevation of the turret of the machine on a somewhat larger scale. Fig. 4, is a view of the same looking in the direction of the arrow, Fig. 3, and showing the gun in section. Fig.

25 Fig. 5, is a sectional view on the line $x-x$ Fig. 3, and Fig. 6, is a sectional view on the line $y-y$ Fig. 4. Fig. 7, is a side elevation showing the adjustment in the tool and not in the turret. Fig. 8, is a perspective view of the tool, and
30 Fig. 9, an enlarged sectional view of the tool.

The machine in general comprises a bed A on which is suitably supported the gun X, the open end of said gun being held in a turret B. On the bed is mounted a carriage C, carrying the tool spindle D, and the carriage is fed along gradually as the cutting proceeds by a screw shaft d, the outer end of which carries a gear d' meshing with a pinion e on the main driving shaft E.

40 On the tool spindle within the carriage is a pinion g which meshes with the rack g' carried on a slide G suitably guided in ways on the upper face of the carriage C, and from this slide G, projects a stud carrying an anti-friction roller h, adapted to the slot of the guiding or rifling cam H, so that as the carriage is moved along the length of the machine by the screw this guiding cam causes the transverse movement of the rack and
45 slide, and thus effects the gradual rotation of

the pinion g, and the tool spindle D, causing the cutting tool carried by the latter to gradually turn as it is fed along and thus effect the desired rifling of the gun.

The turret B comprises a body b within 55 which is a sleeve C', one end forming preferably an integral part of a combined locking and ratchet wheel F, the portion f of which is provided with a series of locking notches with one of which engages a sliding bolt i 60 guided in an extension I of the fixed portion b. The portion f' of this wheel F is provided with a series of ratchet teeth, with one of which engages a detent k, guided in the projecting portion K of the fixed frame b, and 65 under the action of a coiled compression spring k' which always tends to keep it in contact with one or the other of the ratchet teeth.

Pivoted at l to an extension of the portion 70 b is a handled lever L, one arm of which is forked at l', and is adapted to engage with a pin l' projecting from the locking bolt i, and being so arranged that on the movement of the lever in the direction of the arrow Fig. 4, 75 the locking bolt i, will be drawn up out of engagement with the notches of the portion f and the further movement will effect a partial rotation of the body b, and the sleeve F by reason of the engagement of the detent k 80 with one of the ratchet teeth of the portion f'. This adjustment is for the purpose of turning the gun to present to the tool a fresh path to be rifled, and the movement of the parts is transmitted to the gun by a series of clamps 85 m, carried by ring M on the outer end of the sleeve F, the end of the gun being grooved and notched as usual for the engagement of the clamps.

In a great many cases it has been found 90 desirable to give to the gun a very slight turn on its axis independent of the movement of the lever L or the parts to which it is connected, this adjustment being particularly desirable in the event of the breaking or wear- 95 ing of the cutting tool, or when for any other reason a fresh tool has to be employed. To effect this adjustment, I provide the ring M with two projections n' as shown in Fig. 5, and through these projections extend screws 100

p, the inner ends of which bear upon a stud or stop *n*² projecting from the sleeve *C'*, so that the turning of these screws to a greater or less extent will effect a very slight axial movement to the gun with respect to the sleeve, and an adjustment of the utmost nicety may be readily effected, the screws *r* which united the sleeve *C'* to the ring *M* passing through segmental slots which will permit of this slight movement. The same end can be attained by effecting the adjustment in and through the tool, as shown in Figs. 7, 8 and 9. In the modification illustrated in these figures the tool is divided into two parts *D* and *D'* which are provided with flanges *d'* *d*² which are united together by bolts *d*³ which pass through segmental slots in said flanges, as shown, thus permitting, upon loosening of the nuts on said bolts, of slight axial movement of the tool so as to effect the desired adjustment.

Having thus described my invention, what I claim, and desire to secure by Letters Patent, is—

In a gun rifling machine, the combination with a hollow turret, a ring, carrying gun holding and centering clamps, adjustably secured to the turret, said ring being provided with two projections *n* and *n'*, a fixed stud on the turret extending between the said projections, and screws in the projections engaging said stud whereby the ring may be adjusted relatively to the turret, substantially as and for the purpose specified.

In testimony whereof I have hereunto subscribed my name, at Philadelphia, on this 25th day of April, A. D. 1892.

MORRIS F. SMITH.
